HAND GRIP FOR A MOTION PICTURE CAMERA OR SIMILAR ARTICLE

Grant D. Ross, Jr., Lincolnwood, and Simon D. Rydstedt,
Deerfield, Ill., assignors to Bell & Howell Company,
Chicago, Ill., a corporation of Illinois

Filed July 21, 1966, Ser. No. 3,169

Term of patent 14 years

(Cl. D61—1)

FIG. 1 is a front and side perspective view of a hand grip for a motion picture camera or similar article, showing our new design;

FIG. 2 is a side elevational view, the opposite side being substantially a mirror image thereof;

FIG. 3 is a front elevational view;

FIG. 4 is a rear elevational; and

FIG. 5 is a bottom plan view thereof.

The broken-line showing of a camera in FIG. 1 is for illustrative purposes only.

FIGS. 1, 2 and 3 are shaded to indicate contrast in appearance.

We claim:

The ornamental design for a hand grip for a motion picture camera or similar article, as shown and described.
